UNITED STATES PATENT OFFICE.

ANDREAS LIS, OF COVINGTON, KENTUCKY.

DESIGN FOR A CIGAR-BOX.

Specification forming part of Design No. 5,277, dated September 26, 1871.

To all whom it may concern:

Be it known that I, ANDREAS LIS, of Covington, in the county of Kenton and State of Kentucky, have invented and produced a new and original Design for a Cigar-Box, of which the following is a specification:

The accompanying drawing is a perspective view of a cigar-box embodying my design.

The box A is divided into two compartments or receptacles, B B', by means of the partition

C, and said compartments are closed at top by the hinged lids D D'.

I claim as my invention—

The design for a cigar-box, as shown at A B B' C D D' in the annexed illustration.

In testimony of which invention I hereunto set my hand.

Witnesses: ANDREAS LIS.

GEO. H. KNIGHT,

JAMES H. LAYMAN.
